COMBINED MOTION PICTURE PROJECTOR AND CARRYING CASE

Dianne B. Ainslie, Monroe County, N.Y., assignor to Eastman Kodak Company, Rochester, N.Y., a corporation of New Jersey

Filed May 13, 1969, Ser. No. 17,132

Term of patent 14 years

Int. Cl. D16—04

U.S. Cl. D61—1

FIG. 1

FIG. 2

FIG. 4

FIG. 1 is a perspective view of the front, top and one side of a combined motion picture projector and carrying case in accordance with the present invention.

FIG. 2 is in perspective view showing the bottom, rear and other side of the projector of FIG. 1.

FIG. 3 is a view similar to FIG. 1 with the cover removed.

FIG. 4 is a view similar to FIG. 3 showing portions of the projector in an alternate position.

I claim:

The ornamental design for a combined motion picture projector and carrying case, as shown.
